Filed Nov. 20, 1970, Ser. No. 26,087

Term of patent 14 years

Int. Cl. D8—99

U.S. Cl. D8—229

FIG.1

FIG.3

FIG.2

FIG.5

FIG.4

FIG. 1 is a front view of a clamp for connecting tubular members showing my new design;

FIG. 2 is a right side view;

FIG. 3 is a left side view;

FIG. 4 is a top view;

FIG. 5 is a bottom view.

The rear of the clamp for connecting tubular members is a mirror image (with the exception of the screw threads) of the front view shown in the drawing.

The claimed feature of my design resides in the specific configuration of the stirrup and that configuration in relation to and in combination with the wire loop of the clamp for connecting tubular members as best illustrated in FIGS. 1 and 4.

I claim:

The ornamental design for a clamp for connecting tubular members, as shown and described.
